(57) **ABSTRACT**

An atomizer having an atomizer head configured to atomize a first fluid. The atomizer includes, in addition, a measurement module including at least one sensor configured to measure the values of at least one parameter of the atomizer, an electronic control module configured to receive the measured values, and a power supply configured to electrically supply the control module with a power supply voltage.

APPLICATION**

This application claims priority of French Patent Application No. 20 02419, filed on Mar. 11, 2020.

FIELD OF THE INVENTION

The present invention relates to an atomizer. The present invention also relates to an installation equipped with such an atomizer. The present invention relates, moreover, to a method for measuring the values of at least one parameter of such an atomizer.

BACKGROUND OF THE INVENTION

Many fluid atomizing installations include an atomizer, at least one part of which is designed to be brought to a high electrical potential during atomizing. Thus, the difference in electrical potential between the part to be coated with the fluid and the atomizer tends to favor the projection of the fluid droplets projected to the part, since the droplets tend to become electrically charged at the atomizer and follow the electric field lines between the atomizer and the part. The result is an increase in atomizer efficiency, as the amount of fluid that does not reach the part is reduced.

However, the high electrical potentials to which the atomizer head is exposed require electrical insulation between the atomizer head and other parts of the atomizing installation to prevent potentially dangerous arcing. Consequently, the atomizer is equipped with the minimum necessary components and the electrical connections between the atomizer head and the robot on which the atomizer is mounted are arranged in such a way as to isolate the atomizer head from the rest of the installation while allowing a potential difference to be imposed between these elements. When the atomizer is not in operation, the electrical potential is returned to ground so that the atomizer can be moved closer to other parts of the installation or manually operated without risk.

However, the atomizer itself is a complex device including many moving parts such as a bowl rotated at high speed by a turbine, valves to start and stop the supply, to the bowl, of fluid to be atomized, or even a skirt generating precisely controlled air jets to shape the fluid jet optimally. All of these elements must work together to provide high efficiency fluid projection, and the efficiency of the projection rapidly decreases if one or other of these elements are damaged. In addition, there are many external factors that can affect atomizer efficiency and/or the quality of the resulting parts even if the parts making up the atomizer are not damaged.

In general, and in particular because of the high voltage operation, it is difficult to evaluate the performance of the atomizer when it is in operation. As a result, maintenance of the atomizer is made difficult, especially because minor defects or damage are not easily detected, making it impossible to intervene quickly before the negative consequences of these defects are too great. As a result, it is necessary to plan periodic maintenance with a high frequency, which limits the availability of the atomizer. Otherwise, the average quality of the products in the manufacture of which the fluid is used is diminished when the undetected defects of the atomizer result in defects of these products.

2

Even atomizers whose electrical potential does not vary during operation are complex and often difficult to monitor, so they tend to suffer from similar limitations.

Therefore, there is a need for a fluid atomizer with greater availability.

SUMMARY OF THE DESCRIPTION

For this purpose, an atomizer is proposed including an atomizer head configured to atomize a first fluid, the atomizer further including a measurement module with at least one sensor configured to measure values of at least one atomizer parameter, an electronic control module configured to receive the measured values and a power supply configured to provide the control module with a power supply voltage.

The invention allows the state of the atomizer to be monitored during its operation, particularly at high voltage, and to detect events that may occur during this time. As a result, it is easier to detect a dysfunction (or "fault") of the atomizer, including small scale dysfunctions that would otherwise be difficult to detect. As a result, the need for periodic atomizer maintenance is limited, and atomizer availability is improved while providing better average atomizer quality than is possible with state-of-the-art atomizers.

According to particular embodiments, the atomizer has one or more of the following features, taken alone or depending on any technically possible combination:

the atomizer head is configured to be brought to a first electrical potential value when the atomizer is at rest and to a second electrical potential value when the atomizer head is atomizing the first fluid, the second value being strictly higher than the first value, a difference between the first and second values being in particular greater than or equal to 10 kilovolts, the measurement module including a common reference point for the electrical potentials of the measurement module, the reference point being electrically connected to the atomizer head.

the atomizer includes a base intended to be fixed to a robot configured to move the atomizer and including at least one duct for supplying the atomizer head with the first fluid or with a second fluid, the base having a connecting face to which the atomizer head is fixed, the base and the atomizer head being aligned along an axis, the supply duct opening onto the connecting face, the connecting face including at least one valve configured to close off the supply duct, wherein the measurement module includes a ring surrounding the connecting face in a plane perpendicular to the axis.

the ring is configured to associate with the atomizer head and/or the base to prevent fluid splashes from reaching at least one sensor, power supply and/or control module from outside the measurement module.

the atomizer head includes a turbine, a bowl to be rotated by the turbine to atomize the first fluid when the first fluid is injected into the bowl, and a skirt to generate shaping air flows of the atomized first fluid.

the ring is in support against the skirt.

the reference point of the electrical potentials is electrically connected to the skirt.

at least one sensor is an accelerometer, the control module being configured to control a measurement, by the accelerometer, of an acceleration of the atomizer during a rotation of the bowl.

at least one sensor is configured to measure a temperature of the atomizer.

the sensor is configured to measure a skirt temperature. the atomizer furthermore includes at least one valve including a needle that can be moved between two positions, at least one sensor being configured to measure a position of the valve needle.

at least one sensor is an accelerometer, the control module being configured to control a measurement, by the accelerometer, of an acceleration of the atomizer during a movement of the atomizer.

the control module is configured to compare at least one acceleration value measured during a movement of the atomizer to a predetermined threshold and to detect a shock to the atomizer based on the comparison.

at least one sensor is a microphone.

the power supply includes an electrical energy storage device.

An installation is also proposed including a robot equipped with an atomizer as previously described and an electronic analysis device, the control module being configured to generate a diagnostic message from the measured values and to transmit the diagnostic message to the analysis device.

According to particular embodiments, the installation includes one or more of the following features, taken individually or depending on any technically possible combination:

the evaluation device is remote from the robot, the evaluation device being fixed in a reference frame of the installation.

the installation includes a station fixed in a reference frame of the installation, the robot being configured to move the atomizer between an operating position and a data transfer position, the control module being configured to transmit the diagnostic message to the evaluation device, in particular by radio-frequency communication, when the atomizer is in the data transfer position, the station includes a module for receiving the diagnostic message and being configured to transfer the diagnostic message received to the evaluation device. the station is configured to clean the atomizer head when the atomizer is in the data transfer position, the atomizer head being housed within the station when the atomizer is in the data transfer position.

the station has at least one first electrical contact, the atomizer having at least one second electrical contact configured to be connected to the first contact when the atomizer is in the data transfer position, the control module being configured to transmit the diagnostic message to the receiving module via the first and second electrical contacts.

the power supply includes an electrical energy storage device, the station includes a recharging module configured to electrically charge the electrical energy storage device when the atomizer is in the data transfer position. Also provided is a method for measuring at least one parameter of an atomizer including an atomizer head configured to atomize a first fluid and a measurement module including at least one sensor configured to measure values of at least one parameter of the atomizer, an electronic control module configured to receive the measured values and a power supply configured to electrically supply the control module with a power supply voltage, the method including a measurement operation, by the sensor of at least one value of a parameter of the atomizer.

According to one particular embodiment, the measurement module includes a reference point for the electrical potentials of the measurement module, the reference point being electrically connected to the atomizer head, the method including an operation of increasing an electrical potential of the atomizer head from a first value to a second value, the atomizer head having the second electrical potential value during the measurement operation.

10 BRIEF DESCRIPTION OF THE DRAWINGS

Features and advantages of the invention will appear when reading the following description, given only as a non-limiting example, and made with reference to the attached drawings, in which:

FIG. 1 is a schematic representation of a first exemplary fluid projection installation according to the invention, including an atomizer;

FIG. 2 is a schematic representation of an exemplary atomizer from FIG. 1, including a measurement module;

FIG. 3 is a schematic representation of an exemplary measurement module from FIG. 2;

FIG. 4 is a flowchart of the operations of a method implemented by the installation of FIG. 1;

FIG. 5 is a frequency spectrum of a noise acquired by a microphone in the measurement module in FIG. 3, corresponding to a non-defective atomizer;

FIG. 6 is a frequency spectrum of a noise acquired by a microphone in the measurement module in FIG. 3, corresponding to a defective atomizer;

FIG. 7 is a schematic representation of a second exemplary fluid projection installation according to the invention; and

FIG. 8 is a flowchart of the operations in a method implemented by the installation in FIG. 7.

DETAILED DESCRIPTION

40 A first exemplary installation 10 for the projection of a fluid is shown partially in FIG. 1.

Installation 10 includes a robot 15, an atomizer 20, a control module 25 of robot 15, and optionally a first station 35.

45 Installation 10 is configured to atomize a first fluid F.

The first fluid F is, in particular, a coating product such as paint or varnish. For example, the first fluid F is a paint or varnish intended to at least partially, cover a panel P, of a car body.

50 Robot 15 supports atomizer 20. In particular, robot 15 is configured to move atomizer 20 in space, in particular to orientate atomizer 20 in a plurality of directions in space.

In particular, robot 15 is configured to move atomizer 20, 55 within a predetermined reference frame, between an operating position and a rest position, sometimes also referred to as the cleaning position.

The reference frame is a fixed reference frame in relation to a location in installation 10. The reference frame is, for example, the terrestrial reference frame.

In particular, robot 15 is configured to move atomizer 20 between the operating position and the rest position relative to a base 37 of robot 15.

60 A distance between atomizer 20 and first station 35 when atomizer 20 is in the operating position, is strictly greater than a distance between atomizer 20 and first station 35 when atomizer 20 is in the rest position.

Robot **15** is, for example, an articulated arm with actuators to rotate the individual segments of the arm relative to each other to move and orientate atomizer **20** in space.

In addition, robot **15** is designed to supply atomizer **20** with an electrical voltage or current, and with at least a second fluid such as a gas or solvent and a flow of the first fluid F to be atomized.

Alternatively, atomizer **20** includes a reserve of the first fluid F, and therefore does not require a supply of the first fluid F via robot **15**.

The gas G is, for example, air.

Robot **15** is configured to move atomizer **20** in space and/or to orientate atomizer **20** in a plurality of directions in space based on the control messages received from control module **25**. In addition, robot **15** is configured to supply atomizer **20** with electrical voltage or current and/or the first or the first and second fluid(s) based on corresponding control messages.

Atomizer **20** includes, in a manner known per se, a base **40** and an atomizer head **45**. Atomizer **20** also includes a measurement module **30**.

According to one embodiment, atomizer **20** includes a fluid reserve F in a manner known per se, this reserve being, for example, integrated into atomizer head **45** or in base **40**.

Base **40** has a first face which is connected to robot **15** and a second face, also referred to as the connecting face, to which atomizer head **45** is attached.

Base **40** has at least one duct through it that can supply atomizer head **45** with a fluid, such as the fluid F to be atomized. For example, base **40** is traversed from the first face to the connecting face by a plurality of ducts leading to the connecting face.

At least one duct is configured to supply atomizer head **45** with the fluid F to be atomized. At least one other duct is configured to supply atomizer head **45** with the gas G. Optionally, at least one duct is configured to supply atomizer head **45** with a liquid such as a solvent.

In a manner known per se, base **40** includes, for example, at least one valve configured to close or open one of the ducts in base **40**. At least one valve is, for example, located on the connecting face.

Base **40** is, in addition, configured to supply atomizer head **45** with electrical power. For example, the connecting face has an electrical conductor passing through it that is configured to be electrically connected to atomizer head **45** in a manner known per se.

For example, base **40** is configured to impose an electrical potential difference between the first face and the electrical conductor.

In particular, base **40** is configured to change a value of the electrical potential of the electrical conductor between a first value and a second value.

The first electrical potential value is, for example, zero. In this case, the first electrical potential value is equal to an electrical potential value of an electrical ground of installation **10**.

The second electrical potential value is strictly higher than the first electrical potential value. A difference between the first and second electrical potential value is, for example, greater than or equal to 10 kilovolts (kV), for example between 20 kV and 90 kV. It should be noted that the second value may vary, for example during a trajectory of robot **15**.

Base **40** has, for example, an electrical transformer circuit able to generate an electrical voltage equal to the second value of electrical potential between the electrical conductor and ground from an electrical supply voltage.

Atomizer head **45** is configured to atomize fluid F. In particular, atomizer head **45** is configured to atomize fluid F when atomizer head **45** is brought to the second electrical potential value.

5 In a manner known per se, atomizer head **45** consists of a skirt **50**, a bowl **55**, an electrical connector, and a turbine.

In a known manner, atomizer head **45** is configured so that all parts of atomizer head **45** have the same electrical potential. In particular, the electrical potential value of atomizer head **45** is equal to the electrical potential value of the electric conductor of base **40**. Thus, atomizer head **45** is configured to be brought, by base **40**, to the first value and second value of the electrical potential, according to the electrical potential value imposed by base **40** on the electric conductor.

10 Skirt **50** is configured to receive from base **40** a flow of gas G and to generate from the received flow a set of confirmation flows of the projected fluid F.

Bowl **55** is configured to be driven in rotation by the 15 turbine around an axis A1. Bowl **55** is configured to generate a flow of fluid F when fluid F is injected into the bottom of bowl **55** during rotation of bowl **55**.

The electrical connector is electrically connected to skirt **50**, bowl **55**, the turbine, and the electrical conductor of base **40**.

20 Control module **25** is configured to control movement of atomizer **20** by robot **15**.

Control module **25** is, in addition, configured to control a supply to atomizer head **45** with a flow of the fluid F and/or with a flow of the gas G, and/or with a flow of liquid. For example, control module **25** is configured to control the opening and/or closing of each valve on base **40**.

25 In addition, control module **25** is configured to control the change, by base **40**, of the electrical potential of atomizer head **45** from the first value to the second value.

For example, control module **25** includes a processor and memory with software instructions that, when executed on the processor, form a robot **15** motion control module, an atomizer head **45** supply control module, and a control module to change the electrical potential. Alternatively, at least one of these modules is realized as a dedicated integrated circuit, or even programmable logic component.

30 Control module **25** includes, for example, a human-machine interface (HMI), for example, a screen, a keyboard and/or mouse, to enable transmission of information and/or instructions between control module **25** and an operator.

Control module **25** is, for example, a device remote from robot **15**. In particular, control module **25** is fixed in the reference frame.

35 For example, control module **25** is located outside an enclosure defining a volume containing robot **15**.

Measurement module **30** is configured to measure at least one value of a parameter of atomizer **20**. Measurement module **30** is, in addition, configured to transmit to a remote device, for example to control module **25**, at least one message generated, according to the measured value(s).

40 Measurement module **30** includes at least one sensor **60**, a power supply **65**, an electronic control module **70**, and a communication module **75**.

In the first example, measurement module **30** is, for example, attached to atomizer **20**. In this case, measurement module **30** includes, in addition, a first housing **80**.

45 Measurement module **30** is, for example, at least partially housed between base **40** and atomizer head **45**.

In particular, measurement module **30** is traversed by the duct(s) and the electrical conductor connecting base **40** to atomizer head **45**.

According to an embodiment, measurement module 30 at least partially surrounds the connecting face around a second axis A2. In this case, first housing 80 is in the form of a ring at least partially surrounding the connecting face.

For example, the ring completely surrounds the connection surface around the second axis A2, i.e. over 360 degrees. Alternatively, the ring partially surrounds the connection surface. For example, the ring is an annular portion that surrounds the connecting face for 240 degrees or less.

At least one element from a sensor 60, power supply 65, control module 70, and/or the communication module 75 is encapsulated in a sealed manner in ring 80 when measurement module 30 is fixed to atomizer head 45.

“Encapsulate” means that ring 80 is associated with atomizer head 45 and/or base 40 to prevent fluid splashes from reaching any of the above elements from outside measurement module 30.

It should be noted that embodiments in which ring 80 does not provide a seal between the inside and outside of ring 80 are also possible.

In particular, ring 80 surrounds at least one element of a sensor 60, power supply 65, control module 70, and/or communication module 75, in particular, each sensor 60, power supply 65, control module 70, and communication module 75 in a plane perpendicular to the second axis A2.

Alternatively, at least one element from, a sensor 60, power supply 65, control module 70, and/or communication module 75 is embedded in a mass of electrically insulating material, in particular material forming ring 80.

The second axis A2 is perpendicular to the connecting face and is, for example, merged with axis A1.

Base 40 and atomizer head 45 are, for example, aligned along axis A2.

A reference point for the electrical potentials of measurement module 30 is defined.

The reference point is the point from which the electrical potential of each element of measurement module 30, in particular, each sensor 60, power supply 65, electronic control module 70, and communication module 75 are defined.

The reference point is, in particular, the point at which the various electrical currents flowing through measurement module 30 return.

Such a reference point is sometimes referred to as “ground”. In the majority of electrical installations, the reference point is ground.

In other words, measurement module 30 is configured to operate with the reference point as electrical ground.

For example, each sensor 60, power supply 65, electronic control module 70, and communication module 75 are each connected electrically to the reference point, either directly or indirectly.

Measurement module 30 is configured so that the reference point is electrically connected to atomizer head 45. In particular, the reference point is equipotential with the electrical conductor of base 40. I.e., the reference point of measurement module 30 has the same electrical potential as atomizer head 45, and in particular the electrical conductor of base 40.

In particular, the reference point is electrically connected to skirt 50.

For example, measurement module 30 includes an electrical contact 82 resting against atomizer head 45, in particular against skirt 50. It should be noted that there are embodiments in which the reference point is electrically

connected to an element of atomizer head 45 other than skirt 50, for example the turbine or another electrically conductive element.

In this case, electrical contact 82 acts as a reference point for the electrical potential of measurement module 30.

Electrical contact 82 is, for example, electrically connected to control module 70. It should be noted that the common reference point is defined by the various electrical circuits that make up measurement module 30. In addition, embodiments wherein the common reference point is connected to a sensor 60 or even to another element of measurement module 30, are equally possible.

Thus, measurement module 30 is configured to operate by considering as electrical ground, the electrical potential imposed by base 40 on atomizer head 45.

Each sensor 60 is, for example, attached to an inner face 85 of first housing 80. In particular, each sensor 60 is surrounded by inner face 85 in a plane perpendicular to axis A2.

Each sensor 60 is configured to measure the values of a parameter of atomizer 20. In addition, each sensor 60 is configured to transmit the measured values to control module 70.

In particular, each sensor 60 is configured to measure and transmit the values when atomizer 20 is brought to the second electrical potential value, for example while bowl 55 is rotating.

Each sensor 60 is, for example, selected from the list consisting of: an accelerometer, a temperature sensor, a microphone, a valve position sensor of atomizer 20.

It should be noted that other examples of sensors 60 may also be integrated into measurement module 30.

Each accelerometer is configured to measure an acceleration of atomizer 20. For example, the accelerometer is configured to measure acceleration values of atomizer 20 in one direction. Alternatively, the same accelerometer is configured to measure acceleration values of atomizer 20 in two or three directions perpendicular to each other.

In particular, at least one accelerometer is configured to measure acceleration of atomizer 20 in a direction perpendicular to axis A1 of rotation of bowl 55. The measurement of acceleration in this direction allows an imbalance of bowl 55 to be detected, indicative of an imbalance of bowl 55 or a defect of the turbine.

Measurement of acceleration according to one or two other directions allows the detection of too high an acceleration of atomizer 20 during its movement and likely to cause a stall of bowl 55, thus giving an indication of a correction to be made, for example by reducing the acceleration that caused the stall or by modifying a trajectory of atomizer 20.

Each microphone is configured to measure values of noise generated by atomizer 20. The noise is, for example, a noise generated by bowl 55 during rotation of bowl 55.

Each temperature sensor is configured to measure a temperature of atomizer 20.

“Atomizer 20 temperature” is defined as a temperature of an element of atomizer 20, for example, a temperature of atomizer head 45. In particular, each temperature sensor is configured to measure a temperature of skirt 50. Alternatively, at least one temperature sensor is configured to measure a temperature of the turbine, air exhaust duct or another element of atomizer 20.

Each temperature sensor includes, for example, a thermocouple 90 in contact with atomizer head 45, particularly in contact with skirt 50. Thermocouple 90 is, for example,

level with an end face **95** of first housing **80**. However, other types of temperature sensors are also possible.

Each position sensor is configured to measure a position of a valve, for example to measure a stroke of a valve needle integrated in the connecting face between base **40** and head **45** of atomizer **20**.

End face **95** defines first housing **80** along axis **A2** and is opposite atomizer head **45**. In particular, end face **95** rests against skirt **50**.

Another end face **100** defines first housing **80** along axis **A2**, and is opposite base **40**.

Power supply **65** is configured to supply power to control module **70**, to communication module **75**, and to each sensor **60**.

Power supply **65** includes, for example, an energy storage device **105** and a charging device **110**.

Storage device **105** is configured to store electrical energy. For example, storage device **105** includes a capacitor. The capacitor is, for example, a supercapacitor.

Note that other types of electrical energy storage devices are also possible, such as a battery, whether rechargeable or not.

Charging device **110** is configured to receive energy from a device external to measurement module **30**, and to charge storage device **105** with the received energy.

Charging device **110** is, in particular, an inductive charging unit. For example, charging device **110** includes an antenna configured to receive electromagnetic radiation and to generate a potential difference from the received radiation. Charging device **110** is then configured to impose the potential difference on two terminals of measurement unit **105**.

For example, the antenna of charging unit **110** has an electrically conductive winding.

Alternatively, charging device **110** includes two connection terminals carried by an external face **115** of first housing **80**, charging device **110** being configured to transmit to the terminals of measurement unit **105** an electrical potential difference imposed on the two terminals of charging device **110**.

Control module **70** is configured to control the acquisition of values of at least one parameter of atomizer **20** by each sensor **60**.

Control module **70** is configured to control acquisition of at least one value, in particular the atomizer acceleration values, while atomizer head **45** is raised to the second electrical potential value.

In addition, control module **70** is configured to control acquisition of at least one value, in particular atomizer acceleration values, during a bowl rotation.

In addition, control module **70** is configured to control acquisition of at least one value, in particular the atomizer acceleration values, during movement of atomizer **20** by robot **15**.

Control module **70** is configured to generate a diagnostic message from at least one measured value, and to transmit the diagnostic message to communication module **75**.

For example, control module **70** is configured to insert at least one measured value into the diagnostic message. In particular, control module **70** is configured to insert a measured temperature value into the diagnostic message.

The measured temperature value is, for example, measured at the end of a fluid F atomizing operation.

Alternatively, or in addition, control module **70** is configured to calculate at least one diagnostic value from a set of measured values, and to insert the diagnostic value(s) into the diagnostic message.

Each diagnostic value is, for example, a value of an amplitude or frequency of a frequency component, the frequency component being a frequency component of an acceleration or noise measured by the microphone.

5 Each diagnostic value is, for example, calculated from at least one coefficient of a Fourier transform.

The Fourier transform is, for example, a Fourier transform of the measured acceleration values, or of a noise measured by the microphone.

10 Alternatively, the Fourier transform is a Fourier transform of velocity or displacement values of atomizer **20**, these velocity or displacement values being obtained by integration of the measured acceleration values.

According to another variant, each diagnostic value is a coefficient of a Fourier transform of the measured acceleration values, or of a noise measured by the microphone.

15 Alternatively, or in addition, at least one diagnostic value is, for example, a maximum acceleration value of atomizer **20**.

20 Control module **70** is, for example, configured to calculate the values of coefficients and/or frequency and/or amplitude by fast Fourier transform. The Fast Fourier Transform, often referred to as FFT, is an algorithm for calculating a discrete Fourier transform.

25 According to one embodiment, the diagnostic message includes a set of diagnostic values acquired during a rotation of bowl **55**.

30 Alternatively, or in addition, at least one diagnostic value is, for example, an identifier of a dysfunction of atomizer **20** or a shock to atomizer **20**, this dysfunction or shock being detected by control module **70** on the basis of the measured values. For example, the diagnostic message includes an identifier of the dysfunction or shock and an indicator of a time instant, for example, a date and associated time, of the 35 dysfunction or shock.

35 For example, control module **70** includes a processor and memory with software instructions which, when executed on the processor, form an acquisition control module of at least one value by a sensor and a module for generating the 40 diagnostic message. Alternatively, at least one of these modules is realized in the form of dedicated integrated circuits or programmable logic components.

Control module **70**, for example, includes an internal 45 clock. The term "clock" refers to any device that enables control module **70** to measure the passage of time. An example of such a clock is a circuit generating a periodic signal associated to a counter for the number of signal periods.

The clock is, for example, capable of allowing control 50 module **70** to directly measure an elapsed time. In this case, control module **70** is able to associate each event, for example each value measured by a sensor, to a time.

Alternatively, the clock may be used to enable control module **70** to count a number of events, for example to 55 detect a maximum of a periodic signal, and to associate each measured value with an identifier (for example, a number) of one of the events or an interval between two of the events. In this case, control module **70** is not able to directly measure the passage of time, but an external device can 60 establish a correspondence between each identifier and the corresponding time.

Communication module **75** is, particularly, configured to transmit the diagnostic message to a device separate from atomizer **20**. The separate device is, for example, first station 65 **35**.

According to a variant, the separate device is control module **25**.

11

Communication module 75 is, particularly, configured to transmit the diagnostic message via radio frequency communication.

Radio frequency communication is the transmission of messages via a signal including at least one radio frequency electromagnetic wave.

Radio-frequency electromagnetic waves are electromagnetic waves with a frequency between 3 Kilohertz (KHz) and 3 Gigahertz (GHz).

For example, communication module 75 is capable of transmitting or receiving an electromagnetic wave with a frequency greater than or equal to 13.553 MHz and less than or equal to 13.567 MHz.

Preferably, communication module 75 is able to transmit and receive an electromagnetic wave with a frequency greater than or equal to 13.553 MHz and less than or equal to 13.567 MHz.

Advantageously, communication module 75 uses a Near-Field Communication (NFC) protocol. Near-Field Communication is a short-range, high-frequency wireless communication technology that allows the exchange of information between devices up to a distance of approximately 10 centimeters (cm). NFC technology is an extension of ISO/IEC 14443.

Alternatively, communication module 75 is able to transmit or receive an electromagnetic wave with a frequency greater than or equal to 2400 Megahertz (MHz) and less than or equal to 2483.5 MHz.

Preferably, communication module 75 is able to transmit and receive an electromagnetic wave with a frequency greater than or equal to 2400 megahertz (MHz) and less than or equal to 2483.5 MHz.

Advantageously, communication module 75 uses a Bluetooth communication protocol. BLUETOOTH® is a communication standard that allows the bidirectional exchange of data over very short distances. The standards defining Bluetooth protocols are defined by the Bluetooth Special Interest Group.

According to another variant, communication module 75 uses another type of protocol, for example a Wi-Fi protocol. Wi-Fi, also spelled wifi, is a set of wireless communication protocols governed by the IEEE 802.11 group of standards (ISO/IEC 8802-11).

According to another variant, communication module 75 is configured to transmit the diagnostic message via an electrical signal. For example, communication module 75 includes at least one electrical contact that opens on outer face 115 of first housing 80 and is configured to connect to a corresponding electrical contact on first station 35.

It should be noted that embodiments in which communication module 75 is not present are also possible, for example in those cases where the atomizer would be dismantled on a regular basis in order to extract the measured values and/or values that would otherwise be contained in the diagnostic message.

First station 35 is fixed in the reference frame. For example, first station 35 is fixed in relation to base 37 of robot 15.

First station 35 is configured to receive the diagnostic message.

In addition, first station 35 is, in a manner known per se, configured to clean atomizer 20 when atomizer 20 is in the rest position.

Alternatively, or in addition, first station 35 is configured to fill the reserve of fluid F of atomizer 20.

It is noted that embodiments in which first station 35 does not allow cleaning and/or filling of atomizer 20 are also

12

considered. For example, first station 35 has the sole function of receiving the diagnostic message.

First station 35 includes a second housing 120, a receiver module 125, a refill module 127, at least one cleaning nozzle 130, and a refill connector 135.

Second housing 120 defines an opening 140 for receiving atomizer 20. When atomizer 20 is in the rest position, atomizer 20 is at least partially housed in opening 140.

Opening 140 extends, for example, along an axis A3, from an upper face 145 of first station 35. When atomizer 20 is in the rest position, axis A1 is, for example, parallel to axis A3.

Receiver module 125 is configured to receive the diagnostic message and to transmit the diagnostic message to a device configured to allow the exchange of information with an operator, this device being, for example, control module 25. Receiver module 125 and the device to which the diagnostic message is transmitted by receiver module 125 then form a device for evaluating the diagnostic message.

For example, receiver module 125 has an antenna configured to receive the diagnostic message.

Receiver module 125 is, for example, carried by upper face 145 of second housing 120. In particular, receiver module 125 is opposite measurement module 30 when atomizer 20 is in the rest position.

When atomizer 20 is in the rest position, a distance between receiver module 125 and communication module 75 is less than or equal to 15 centimeters.

Alternatively, receiver module 125 includes at least one electrical contact configured to contact an electrical contact on measurement module 30 when atomizer 20 is in the rest position to receive the diagnostic message as an electrical signal.

Recharge module 127 is configured to recharge storage device 105 when atomizer 20 is in the rest position.

For example, recharge module 127 is configured to generate a variable electromagnetic field that will generate an electrical potential difference at the terminals of charging device 110. For example, charging module 127 include an electrically conductive winding in which charging module 127 is configured to circulate an alternating electric current to generate the variable electromagnetic field.

A distance between charging module 127 and charging device 110, when atomizer 20 is in the rest position, is less than or equal to 5 centimeters.

Many types of induction charging modules 127 are used for many applications such as cell phone charging.

In a manner known per se, cleaning nozzle 130 is configured to clean atomizer head 45 when atomizer 20 is in the rest position, particularly by atomizing a flow of liquid, particularly a solvent, onto atomizer head 45.

Filling connector 135 is, in a known manner, configured to inject fluid F reserve into atomizer 20, when atomizer 20 is in the rest position.

The operation of installation 10 will now be explained with reference to FIG. 4, which shows a flow chart of the operations in a method for measuring at least one parameter of atomizer 20.

The method includes an initial operation 200, a first displacement operation 210, an atomizing operation 220, a second displacement operation 230 and a transfer operation 240.

In initial operation 200, atomizer 20 is in the rest position.

In initial operation 200, atomizer 20 has the first electrical potential value.

In first displacement operation 210, control module 25 controls a displacement of atomizer 20 to the operating position.

13

In addition, control module 70 controls the measurement of acceleration values, by the accelerometer(s) of atomizer 20 during movement of atomizer 20.

For example, each accelerometer acquires acceleration values with a time period between 500 Hz and 5 kHz, for example equal to 3 kHz.

Each value measured by a sensor 60 is transmitted to control module 70 and stored in the memory of control module 70.

During displacement operation 210, for example after movement of atomizer 20, control module 25 controls the change of the electrical potential of atomizer head 45, via base 40, from the first value to the second value.

In atomizing operation 220, atomizer 20, in its operating position, atomizes fluid F.

In atomizing operation 220, atomizer head 45 has the second electrical potential value.

For example, in a manner known per se, a potential difference equal to the second electrical potential value is imposed between an object P that is to be coated with fluid F and atomizer head 45. In particular, the object P is grounded.

In particular, the reference point of the electrical potentials has the second electrical potential value.

In order to atomize fluid F, bowl 55 is rotated around its axis and fluid F is injected into bowl 55 to generate the fluid jet F. In addition, the skirt generates gas jets G intended to shape the fluid jet F.

During atomizing operation 220, control module 70 controls acquisition of at least one value by at least one sensor 60.

For example, control module 70 controls acquisition of a set of acceleration values of atomizer 20 by one or more accelerometer(s) during rotation of bowl 55.

Alternatively, or in addition, control module 70 controls acquisition of values of noise emitted by bowl 55 during its rotation.

Alternatively, or in addition, during atomizing operation 220, one of sensors 60 measures position values of the needle position of the corresponding valve.

For example, in atomizing operation 220, the valve needle is switched between an open configuration in which fluid F, or air, may flow through the valve, and a closed configuration in which the valve is sealed against fluid F or air. Sensor 60 measures needle position values during needle switching.

In addition, control module 70 controls acquisition of a set of temperature values from atomizer head 45, particularly from skirt 50. The temperature values are, for example, acquired with a time period between 1 second and 2 minutes. In particular, at least one temperature value is acquired during each painting cycle.

Each value measured by a sensor 60 is transmitted to control module 70 and stored in the memory of control module 70.

In the second movement operation 230, control module 25 controls movement of atomizer 20 by robot 15 to the rest position.

In addition, control module 25 controls the change of the electrical potential of atomizer head 45 from the second value to the first value. For example, the electrical potential of atomizer head 45 reaches the first value before movement of atomizer 20, or even during movement of atomizer 20 to the rest position.

In addition, control module 70 controls the acquisition of acceleration values during movement of the atomizer from the operating position to the rest position.

14

Optionally, at least one temperature value is acquired during the second measuring operation.

Each value measured by a sensor 60 is transmitted to control module 70 and stored in the memory of control module 70.

During transfer operation, the diagnostic message is transmitted directly from communication module 75 to receiver module 125. According to a variant, the diagnostic message is transmitted directly from communication module 75 to control module 25.

For example, the diagnostic values are generated by control module 70 from the values measured in transfer operation 240. Alternatively, at least one diagnostic value is generated in first movement operation 210, the atomizing operation 220, and/or second movement operation 230. According to an embodiment, the calculation of the diagnostic values is carried out continuously, whereby each new measured value is included in the calculation of the diagnostic values as soon as possible after the acquisition of the value.

At least one diagnostic value is, for example, a maximum value among the acceleration values acquired during each of movement operations 210 and 230.

Each value stored in control module 70 is time-stamped; i.e. associated to a value acquisition date or an identifier of the acquisition date, which control module 25 is configured to convert into the acquisition date.

The diagnostic values include, in addition, a set of amplitude values of frequency components acquired during rotation of bowl 55. Frequency components are frequency components of the measured acceleration and/or noise.

For example, the diagnostic values include, for a set of predetermined frequency components, an amplitude value of each frequency component. The set of amplitude values then forms a frequency spectrum of the acceleration of atomizer 20 or the noise emitted by atomizer 20 during rotation of bowl 55.

Alternatively, the diagnostic values include, for each of a set of frequency ranges, a value showing the amplitudes of the frequency components of the frequency range under consideration. The representative value is, for example, an average of the amplitudes of the frequency components of the frequency range in question.

Alternatively, or in addition, diagnostic values include a frequency value of a frequency component of the measured acceleration, the frequency value being the value related to the highest amplitude.

The set of diagnostic values includes, for example, a minimum and a maximum value of the measured temperature values.

Alternatively, or in addition, the diagnostic values include, for example, a value for the duration of a valve switchover (also referred to as "response time") or a value for the needle movement between the open and closed valve configurations, which are calculated by control module 70.

"Switching time" means, for example, the duration of the needle movement between the open and closed configuration of the valve or vice versa.

The diagnostic message is transmitted from receiver module 125 to control module 25.

In transfer operation 240, storage device 105 is electrically charged by charging module 127.

In addition, atomizer head 45 is cleaned by first station 35 during transfer operation 240. Optionally, the fluid reserve F of atomizer 20 is filled via filling connector 135.

Control module 25 compares, for example, the frequency spectrum contained in the diagnostic values with a reference

15

spectrum and detects a dysfunction of bowl 55, for example an imbalance of bowl 55, from the comparison. For example, if a difference between an amplitude value contained in the diagnostic message and an amplitude value, associated to the same frequency, of the reference spectrum is greater than or equal to a threshold, a dysfunction is detected. Alternatively, the compared values are values showing the amplitudes of the same frequency range, respectively from the reference spectrum and the diagnostic message.

If at least one acceleration value measured during movement operations 210 and 230 is greater than or equal to a predetermined threshold, control module 25 detects a shock of robot 15 or atomizer 20.

Control module 25 signals any detected dysfunction or shock to the operator, for example via a corresponding display on a screen.

Each detected shock is associated, on the screen, to the date of the shock, estimated from the time stamp of each acceleration value greater than or equal to the threshold. For example, a position of robot 15 at the time of the shock is displayed on the screen.

The maximum and minimum measured temperature values are also displayed on the screen.

Note that if communication module 75 is configured to transmit the diagnostic message to a device separate from first station 35, for example directly to control module 25, the transfer operation 240 may be performed while atomizer 20 is not in the rest position, for example while moving atomizer 20 from the operating position to the rest position.

Since the electrical potential reference point of measurement module 30 is electrically connected to atomizer head 45, measurement module 30 allows the parameter values of atomizer 20 to be measured during the operation of atomizer 20, particularly when atomizer head 45 is brought to a high electrical potential in relation to the rest of installation 10. Thus, measurement module 30 allows maintenance of installation 10 to be carried out as soon as a malfunction of atomizer 20 is detected. In addition, performing measurements while atomizer head 45 is at a high electrical potential allows access to information that would not otherwise be available, for example, to detect a shock taking place at that time, and also avoids slowing down the operation of the installation by providing a specific time range for performing the measurements.

It should be noted that measurement module 30 includes sensors 60 that are also likely to be used in installations wherein the electrical potential of atomizer 20 is not changed during atomizing, and therefore allows better detection of dysfunctions or incidents related to atomizer 20. In this case, the reference point of the electrical potentials is not necessarily connected to atomizer head 45.

Measurement module 30 integrated in a ring surrounding the connecting face between base 40 and atomizer head 45 allows measurement module 30 to be adapted to existing installations with the minimum of modifications to base 40 and/or atomizer head 45, since rings are already provided at this location to protect the valves passing through the connecting face.

Attaching the various components 60, 65, 70, 75 of measurement module 30 to the inner face of the ring makes manufacturing of measurement module 30 easier, while making it easy to install and allowing a high accuracy of the measurements performed.

The support of ring 80 of measurement module 30 against skirt 50 makes it possible to measure the parameters of skirt 50 easily, particularly its temperature, and to measure with

16

great precision the parameters of atomizer 20 because of the large contact surface between atomizer 20 and measurement module 30.

Electrically connecting the reference point of measurement module 30 to skirt 50 allows the reference point to be set to the same potential as atomizer head 45 simply and reliably.

By measuring acceleration of the atomizer 20 with an accelerometer of measurement module 30, shocks to robot 15 or to atomizer 20 may be detected, as well as a dysfunction of atomizer 20, particularly an imbalance of bowl 55 due to a deformation of bowl 55 as a result of a shock, or a dysfunction of the turbine.

Measuring acceleration during movement of atomizer 20 allows, particularly, to detect a shock during this movement and thus to adapt the trajectory of robot 15 if necessary. For this, by comparing the acceleration values with a threshold, a shock can be detected in a simple way.

By measuring acceleration during a rotation of bowl 55, an imbalance in bowl 55 may be detected.

Measuring temperature of atomizer 20 allows detection of excessive cooling due to the expansion of the gases used to shape the jet of fluid F or to drive the turbine in rotation, and thus to prevent the condensation of water vapor on atomizer 20 from having harmful effects on the quality of the part that is to be coated with fluid F, either by interfering with atomization or by droplets of water falling on the part. Measuring the temperature of skirt 50 provides reliable information showing the condition of atomizer 20, since skirt 50 represents a large part of the surface of atomizer head 45.

A microphone may also be used to detect an imbalance of bowl 55, for example a deformation of bowl 55 or a spatial disorientation with respect to axis A1, from noise emitted by bowl 55 during its rotation.

In particular, FIG. 5 shows a graph 250 of a frequency spectrum of the noise measured during rotation of a non-defective bowl 55 at 25,000 rpm. Particularly, an amplitude A (in arbitrary units) of frequency components of the measured noise is shown as a function of the frequency f (in arbitrary units).

FIG. 6 shows a graph 255 of a frequency spectrum of the noise measured during rotation of a defective bowl 55 at 25,000 rpm. Particularly, an amplitude A (in arbitrary units) of frequency components of the measured noise is shown as a function of frequency f. It thus appears that the comparison of the two spectra, and particularly the comparison at a threshold of one or more differences, each difference being a difference between amplitudes associated with the same frequency, allows the detection of a defective bowl 55.

The integration of receiver module 125 at first station 35 allows an existing installation to be easily adapted and allows transfer of information from the measurement without additional loss of time during cleaning of atomizer 20. The use of a radio frequency diagnostic message also reduces the need for modifications to installation 10, since the trajectory of atomizer 20 does not have to be changed to make contact with electrical connectors to transfer the diagnostic message. This limits the risk of arcing or soiling of installation 10.

If, on the other hand, the diagnostic message is transmitted by an electrical signal, the power consumption of measurement module 30 is limited.

The presence of storage device 105 and its charging by station 35, in particular by induction, again minimizes the need for adjustments to installation 10.

17

A second exemplary installation 10 will now be described. The elements identical to the first example are not described again. Only the differences are highlighted.

The second exemplary installation 10 is shown in FIG. 7.

The second exemplary installation 10 may contain an atomizer 20 whose electrical potential is not changed during operation, for example an atomizer 20 connected to ground during atomizing.

Measurement module 30 is connected to first station 35. In particular, measurement module 30 is not mounted on or connected to atomizer 20.

Robot 15 is able to move atomizer 20 in relation to measurement module 30.

When atomizer 20 is in the rest position, a distance between atomizer 20 and measurement module 30 is less than or equal to 20 centimeters (cm). For example, atomizer 20 is in contact with first station 35, in particular with measurement module 30. In particular, skirt 50 is in contact with measurement module 30 when atomizer 20 is in the rest position.

Measurement module 30 is configured to measure values of the atomizer parameters when atomizer 20 is in the rest position.

Measurement module 30 at least partially surrounds axis A3 of opening 140. In particular, measurement module 30 at least partially surrounds atomizer 20 when atomizer 20 is in the rest position.

Housing 80 of measurement module 30 forms a ring, for example at least partially defining opening 140 in a plane perpendicular to axis A3. The ring then forms, for example, an inner wall of first station 35.

Alternatively, housing 80 forms a ring partially surrounding axis A3, for example over an angle of 240 degrees or less. Please note that the positioning and shape of housing 80 may vary.

In particular, each sensor 60 is attached to the ring. For example, each sensor 60 is carried by and attached to the ring. For example, each sensor 60 is fixed to wall 85 of the ring that defines opening 140. In particular, each sensor 60 is arranged radially outside wall 85 of the ring that defines opening 140. Thus, sensors 60 are protected against possible splashes and electrically isolated from the rest of the installation by wall 85.

The temperature sensor is, for example, configured to be in contact with atomizer head 45, particularly skirt 50, when atomizer 20 is in the rest position. The temperature sensor extends, in particular, through the ring formed by housing 80.

Each accelerometer is configured to measure acceleration values of first station 35, in particular of measurement module 30.

A method for measuring at least one parameter of atomizer 20, implemented by the second exemplary installation 10, will now be described.

The method includes an atomizing operation 220, a movement operation 230, and a measuring operation.

In atomizing operation 220, atomizer 20, in its operating position, atomizes fluid F.

In atomizing operation 220, atomizer head 45 has the second electrical potential value.

For example, in a manner known per se, a potential difference equal to the second electrical potential value is imposed between an object P that is to be coated with fluid F and atomizer head 45. In particular, object P is grounded.

18

In order to atomize fluid F, bowl 55 is rotated around its axis and fluid F is injected into bowl 55 to generate the jet of fluid F. In addition, skirt 50 generates gas jets G intended to shape the jet of fluid F.

5 In movement operation 230, atomizer 20 is moved by robot 15 from the operating position to the rest position. In addition, the electrical potential of atomizer 20 is changed from the second value to the first value.

During the measurement operation, bowl 55 is rotated 10 around its axis. For example, control module 70 controls rotation of bowl 55.

Acceleration values of first station 35 are measured by each accelerometer during rotation of bowl 55.

In addition, at least one temperature value of atomizer 15 head 45, in particular of skirt 50, is measured by a temperature sensor when atomizer 20 is in the rest position.

The diagnostic values are generated in a similar way to the first exemplary installation, the acceleration values used are 20 acceleration values of first station 35 and not acceleration values of atomizer 20.

Placing measurement module 30 in first station 35 simplifies measurement module 30, which no longer has to be connected to high voltage. In addition, measurement module 30 does not need to carry an electrical energy storage device 105.

Furthermore, it is not necessary to modify an already existing atomizer 20 to allow measurement of parameters.

In addition, measurement module 30 may also transmit 30 information in a wired analog way or via a wired network, which has the advantage of being less subject to the surrounding electromagnetic constraints than a wireless transmission.

The calculation and local storage of faults in the microprocessor embedded in control module 70 is no longer 35 necessary.

Finally, measurement module 30 located in first station 35 is not subject to overspray (i.e., fluid splashes) that would occur during the application.

If first station 35 is a station used for cleaning and/or 40 filling atomizer 20, installation 10 may be easily obtained by limited modification of an existing installation.

When measurement module 30 forms a ring 80 surrounding atomizer 20 when the latter is in the second position, numerous sensors 60 may be brought into contact with 45 atomizer 20, in particular when sensors 60 are attached to the wall of ring 80 which defines the opening. In addition, measurement module 30 may be installed on a cleaning station 35 of a known type, by arranging measurement module 30 in such a way that measurements are taken when 50 atomizer 20 is in the position in which it is cleaned.

In particular, a microphone may be used to detect a dysfunction of bowl 55 even if there is no contact between atomizer 20 and first station 35. This makes the measurement exceptionally reliable as it does not depend on the 55 quality of the support between atomizer 20 and first station 35.

When first station 35 is separate from the station used for cleaning and/or filling atomizer 20, first station 35 may be used to measure parameters of atomizer 20 that would be incompatible with too close a proximity to this cleaning station; for example, measurement of the second electrical potential value. Indeed, first station 35 may be electrically isolated from the rest of installation 10, much more easily than such isolation of the cleaning station would be.

65 The measurement of the electrical potential of atomizer 20 allows detection of dysfunctions related to the power supply of atomizer head 45, in particular a drift of the second

19

electrical potential value which could lead to imperfect atomizing if the second value is too low.

The use of a station 35 able to move measurement module 30 allows such an isolation in an easy way, since in particular measurement module 30 is likely to be moved away from the other devices of installation 10 when it is brought closer or brought into contact with atomizer 20 to carry out the measurement.

The use of a station 35 fixed in the reference frame of installation 10 simplifies installation 10.

According to a variant of the second example, measurement module 30 is not coaxial with opening 140. For example, measurement module 30 is arranged on a lateral face of first station 35. In this case, the rest position is not a cleaning position. Atomizer 20 is cleaned and/or filled with fluid F in a cleaning position in which measurement module 30 is at least partially housed in opening 140.

This variant may be easier to integrate depending on the dimensions of atomizer 20 and the first existing stations 35.

According to another variant, measurement module 30 is not in contact with atomizer 20 when atomizer 20 is in the rest position.

In this case, measurement module 30 is, for example, without an accelerometer.

At least one sensor 60 is, for example, configured to measure an acceleration, speed or displacement of atomizer 20 without contact with atomizer 20, for example by reflection of a laser beam on the outer surface of atomizer 20.

Alternatively, or in addition, at least one sensor 60 is configured to measure a noise emitted by bowl 55 during its rotation.

Each temperature sensor is, for example, configured to measure a temperature of atomizer 20, in particular of skirt 50, by measuring an infra-red radiation emitted by atomizer 20.

According to a third exemplary installation 10, installation 10 includes, in addition to first station 35, a second station.

First station 35 contains measurement module 30. For example, measurement module 30 is mounted on a movable arm of first station 35, first station 35 being configured to move measurement module 30 between a first position in which measurement module 30 is remote from atomizer 20 when the atomizer is in the rest position, and a second position in which measurement module 30 is in contact with atomizer 20 when the atomizer is in the rest position.

The second station is, for example, fixed in relation to base 37 of robot 15.

The second station has opening 140, cleaning nozzle 130, and filling connector 135.

Measurement module 30 includes, for example, in addition to sensors 60 already mentioned, a sensor 60 configured to measure an electrical potential value of atomizer 20 when measurement module 30 is in contact with atomizer 20.

A method for measuring at least one parameter of atomizer 20, implemented by the third exemplary installation 10, will now be described.

The method includes an atomizing operation 300, a first movement operation 310, a measurement operation 320 and, optionally, a second movement operation 330, and a maintenance operation 340. A flowchart of the operations in this method is shown in FIG. 8.

Note that the order of operations 300 to 340 is subject to change.

In atomizer operation 300, atomizer 20, in its operating position, atomizes fluid F.

20

In atomizing operation 300, atomizer head 45 has the second electrical potential value.

For example, in a manner known per se, a potential difference equal to the second electrical potential value is imposed between an object P that is to be coated with fluid F and atomizer head 45. In particular, object P is grounded.

In order to atomize fluid F, bowl 55 is rotated around its axis and fluid F is injected into bowl 55 to generate the jet of fluid F. In addition, skirt 50 generates gas jets G intended to shape the jet of fluid F.

In first movement operation 310, atomizer 20 is moved by robot 15 from the operating position to the rest position. In addition, measurement module 30, if mobile, is moved to its second position.

The electrical potential of atomizer 20 remains fixed at the second value by base 40 of atomizer 20 during first movement operation 310.

At least one value of the electric potential of atomizer 20, in particular the electric potential of skirt 50, is measured during measurement operation 320. In particular, the second electric potential value is measured.

After measurement of the value of the electric potential, the electric potential of atomizer 20 is changed from the second value to the first value.

In measurement operation 320, bowl 55 is rotated around its axis. For example, control module 70 controls the rotation of bowl 55.

Acceleration values of measurement module 30 are measured by each accelerometer during rotation of bowl 55.

In addition, at least one temperature value of atomizer head 45, in particular of skirt 50, is measured by a temperature sensor when atomizer 20 is in the rest position.

The diagnostic values are generated in a similar way to the first exemplary installation, with the acceleration values used being acceleration values from first station 35 and not acceleration values from atomizer 20.

After measurement operation 320, atomizer 20 is moved by robot 15 to a cleaning position in which atomizer 20 is at least partially housed in opening 140 of the second station.

Atomizer 20 is cleaned and/or the reserve filled with fluid F in maintenance operation 340 in a manner known per se.

The third example particularly allows the electrical potential to be measured, in particular when the electrical potential has the second value, even if this second value is extremely high compared to that of the rest of installation 10. Since measurement module 30 is not integrated into the station intended to clean the atomizer or fill the reserve but in a dedicated station 35, this station 35 is easier to isolate from the rest of installation 10.

According to a variant, at least two first stations 35 are present. For example, one of the first stations 35 includes the electrical potential sensor 60, and the other first station 35, or the second station, includes the other sensors 60. This embodiment limits, in particular, the risk that the high potential of atomizer 20 will cause damage to the other sensors 60 or related devices.

It should be noted that in the second or third example, the measurement of a potential value by a station 35 is optional. Depending on the possible embodiments, the values of other parameters of the atomizer are carried out, without a potential value being measured.

The invention claimed is:

1. An atomizer comprising:
an atomizer head configured:
to atomize a first fluid, and
to be brought to a first electrical potential value when
the atomizer is at rest and to a second electrical

21

- potential value when the atomizer head atomizes the first fluid, the second value being strictly higher than the first value;
- a base for attachment to a robot configured to move the atomizer, the base comprising:
- at least one duct for supplying said atomizer head with the first fluid or with a second fluid; and
  - a connecting face to which said atomizer head is attached, the base and said atomizer head being aligned along an axis, the at least one supply duct opening onto the connecting face, and the connecting face comprising at least one valve configured to close the at least one supply duct;
  - a measurement module comprising:
    - a ring surrounding the connecting face in a plane perpendicular to the axis;
    - at least one sensor configured to measure the values of at least one parameter of the atomizer;
    - an electronic control module configured to receive the measured values;
    - a power supply configured to electrically supply said control module with a power supply voltage; and
    - a common reference point of electrical potentials of the measurement module, the reference point being a point from which an electrical potential of each of said at least one sensor, said power supply and said electronic control module are defined, the reference point being electrically connected to said atomizer head, the reference point of the measurement module having the same electrical potential as said atomizer head, the reference point having the second electrical potential value when said atomizer head atomizes the first fluid.
2. The atomizer according to claim 1, wherein said atomizer head comprises:
- a turbine;
  - a bowl able to be rotated by the turbine to atomize the first fluid when the first fluid is injected into the bowl; and
  - a skirt for generating shaping air flows of the atomized first fluid, wherein the reference point of the electrical potentials is electrically connected to said skirt.
3. The atomizer according to claim 1, wherein a difference between the first and second values is greater than or equal to 10 kilovolts.
4. The atomizer according to claim 1, wherein said ring is configured to associate with said atomizer head and/or said base, to prevent splashing fluid from reaching said at least one sensor, said at least one supply duct, and/or said control module from outside said measurement module.
5. The atomizer according to claim 1, wherein said atomizer head comprises:
- a turbine;
  - a bowl able to be rotated by said turbine to atomize the first fluid when the first fluid is injected into the bowl; and
  - a skirt for generating shaping air flows of the atomized first fluid, in which said ring rests against the skirt.
6. The atomizer according to claim 1, wherein said atomizer head comprises:
- a turbine;
  - a bowl able to be rotated by said turbine to atomize the first fluid when the first fluid is injected into the bowl; and
  - a skirt for generating shaping air flows of the atomized first fluid.

22

7. The atomizer according to claim 6, wherein at least one of said at least one sensor is an accelerometer, said control module being configured to control a measurement, by the accelerometer, of an acceleration of the atomizer during a rotation of said bowl.
8. The atomizer according to claim 1, wherein at least one of said at least one sensor is configured to measure a temperature of the atomizer.
9. The atomizer according to claim 6, wherein said at least one sensor is configured to measure a temperature of said skirt of said atomizer head.
10. The atomizer according to claim 1, wherein at least one of said at least one sensor is an accelerometer, said control module being configured to control a measurement, by the accelerometer, of an acceleration of the atomizer during a movement of the atomizer.
11. The atomizer according to the claim 10, wherein said control module is configured to compare at least one acceleration value measured during a movement of the atomizer with a predetermined threshold, and to detect a shock to the atomizer based on the comparison.
12. The atomizer according to claim 1, wherein at least one of said at least one sensor is a microphone.
13. The atomizer according to claim 1, wherein said power supply comprises an electrical energy storage device.
14. An installation comprising:
- the robot equipped with the atomizer according to claim 1; and
  - an electronic evaluation device,
- 30 wherein the control module of said atomizer is configured to generate a diagnostic message from the measured values and to transmit the diagnostic message to said evaluation device.
15. The installation according to claim 14, in which said evaluation device is remote from said robot, said evaluation device being fixed in a reference frame of the installation.
16. The installation according to claim 15, further comprising a station fixed in the reference frame of the installation, wherein said robot is configured to move said atomizer between an operating position and a data transfer position, wherein the control module of said atomizer is configured to transmit the diagnostic message to said evaluation device by radiofrequency communication when said atomizer is in the data transfer position, said station comprising a module for receiving the diagnostic message and configured to transfer the received diagnostic message to said evaluation device.
17. The installation according to claim 16, wherein said station is configured to clean the atomizer head when said atomizer is in the data transfer position, the atomizer head being housed within said station when the atomizer is in the data transfer position.
18. The installation according to claim 16, wherein said station comprises at least one first electrical contact, and wherein said atomizer comprises at least one second electrical contact configured to be connected to said first contact when said atomizer is in the data transfer position, the control module of said atomizer being configured to transmit the diagnostic message to the receiver module of said atomizer via the first and second electrical contacts.
19. The installation according to claim 16 wherein the power supply of said atomizer comprises an electrical energy storage device, and wherein said station comprises a charging module configured to electrically charge the electrical energy storage device when said atomizer is in the data transfer position.
